The dominant features of my design reside in the portions shown in full lines.

I claim:

The ornamental design of a cart, substantially as shown and described.
